TRIAMINE ACID ADDITION SALTS OF CAPRYLIC, PROPIONIC AND UNDECYLENIC ACIDS

Michael G. Mulinos, Westfield, N.J., assignor to Commercial Solvents Corporation, a corporation of Maryland
No Drawing. Filed Sept. 19, 1960, Ser. No. 56,661
9 Claims. (Cl. 260—404.5)

My invention relates to alkyl triamines and more particularly it relates to acid addition salts of alkyl triamines which salts possess antifungal activity.

U.S. Patent 2,436,779 by Murray Senkus describes certain alkyl triamines including some of the compounds from which my new acid addition salts are prepared. Similarly copending application Serial No. 738,928 filed June 2, 1958, now abandoned, by John B. Tindall describes applicable alkyl triamines.

In the past many compounds have been discovered to have antibacterial activity, but comparatively few have been found to have antifungal activity permitting therapeutic use at practical levels. Further consideration must also be given to toxicity, especially the topical irritation and skin sensitization (allergenicity) frequently encountered in the use of prior antifungal agents.

I have now discovered new compositions possessing practical antifungal activity which new compositions are essentially non toxic when employed in amounts adequate to eradicate fungal infections caused by susceptible fungi.

The new triamine acid addition salts of my invention have the following general formula:

wherein R consists of groups selected from the class consisting of hydrogen and methyl, with the proviso that if one R is methyl, then the other R must be hydrogen; R¹ consists of groups selected from the class consisting of caprylic, propionic or undecylenic acids, and x is either 0 or 1, with the proviso that at least one x is 1.

Illustrative of compounds included in the above general formula are

- N¹,2-dimethyl-N¹,N³-bis(2-ethylhexyl)-1,2,3-propanetriamine mono-propionate,
- N¹,2-dimethyl-N¹,N³-bis(2-ethylhexyl)-1,2,3-propanetriamine dipropionate,
- N¹,2-dimethyl-N¹,N³-bis(2-ethylhexyl)-1,2,3-propanetriamine tripropionate,
- N¹,2-dimethyl-N¹,N³-bis(2-ethylhexyl)-1,2,3-propanetriamine monocaprylate,
- N¹,2-dimethyl-N¹,N³-bis(2-ethylhexyl)-1,2,3-propanetriamine dicaprylate,
- N¹,2-dimethyl-N¹,N³-bis(2-ethylhexyl)-1,2,3-propanetriamine tricaprylate,
- N¹,2-dimethyl-N¹,N³-bis(2-ethylhexyl)-1,2,3-propanetriamine mono-undecylenate,
- N¹,2-dimethyl-N¹,N³-bis(2-ethylhexyl)-1,2,3-propanetriamine diundecylenate,
- N¹,2-dimethyl-N¹,N³-bis(2-ethylhexyl)-1,2,3-propanetriamine triundecylenate,
- N¹,N³-bis(2-ethylhexyl)-2-methyl-1,2,3-propanetriamine mono-propionate,
- N¹,N³-bis(2-ethylhexyl)-2-methyl-1,2,3-propanetriamine dipropionate,
- N¹,N³-bis(2-ethylhexyl)-2-methyl-1,2,3-propanetriamine tripropionate,
- N¹,N³-bis(2-ethylhexyl)-2-methyl-1,2,3-propanetriamine mono-caprylate,
- N¹,N³-bis(2-ethylhexyl)-2-methyl-1,2,3-propanetriamine dicaprylate,

2

N¹,N³-bis(2-ethylhexyl)-2-methyl-1,2,3-propanetriamine tricaprylate,

N¹,N³-bis(2-ethylhexyl)-2-methyl-1,2,3-propanetriamine mono-undecylenate,

5 N¹,N³-bis(2-ethylhexyl)-2-methyl-1,2,3-propanetriamine diundecylenate,

N¹,N³-bis(2-ethylhexyl)-2-methyl-1,2,3-propanetriamine triundecylenate

and the like.

In preparing the triamine acid addition salts of my invention, I utilize the corresponding triamine. The corresponding triamines have the following general formula:

wherein R consists of groups selected from the class consisting of hydrogen and methyl with the proviso that if one R is methyl, then the other R must be hydrogen.

20 The selected triamine is then reacted with propionic, caprylic or undecylenic acids.

The triamine acid addition salts of my invention are prepared by mixing 1 mole of the corresponding triamine with 1, 2, or 3 moles of caprylic, propionic or undecylenic acid. Furthermore, mixtures of the three acids can be used. For instance, I can mix 1 mole of N¹,N³-bis(2-ethylhexyl)-2-methyl-1,2,3-propanetriamine with 1 mole of caprylic and 2 moles of undecylenic acids, or I can mix 1 mole of N¹,N³-bis(2-ethylhexyl)-2-methyl-1,2,3-propanetriamine with 2 moles of propionic acid, etc.

25 When utilizing N¹,2-dimethyl-N¹,N³-bis(2-ethylhexyl)-1,2,3-propanetriamine, as the triamine starting material, it can be prepared according to the disclosure of copending application Serial No. 738,928 filed June 2, 1958

30 by John B. Tindall.

Whereas, when utilizing N¹,N³-bis(2-ethylhexyl)-2-methyl-1,2,3-propanetriamine, as the triamine starting material, it can be prepared according to the disclosure of U.S. Patent No. 2,436,779.

35 The new compounds of my invention are uniquely suited for use as antifungal agents. For example, they can be incorporated in soaps and other suitable vehicles to enhance the normal washing activity of soaps with antifungal properties. My new compounds can also be used in shampoos to give antifungal properties to shampoos and thereby give antifungal protection to those areas or objects washed with these cleansers.

40 A therapeutic antifungal foot powder can be prepared by mixing 0.5 to 5.0 grams of N¹,2-dimethyl-N¹,N³-bis(2-ethylhexyl)-1,2,3-propanetriamine tricaprylate with 10.0 grams boric acid, 20.0 grams of starch and enough talc to make a 100.0 gram composition.

45 Similarly my compounds can be used to impart antifungal activity to ointments and lotions. For instance a very fine washable therapeutic ointment can be prepared by mixing 0.5 to 5.0 grams of N¹,2-dimethyl-N¹,N³-bis(2-ethylhexyl)-1,2,3-propanetriamine tripropionate with enough hydrophilic ointment (U.S.P.) to make 100 grams of ointment.

50 Furthermore a nonwater washable therapeutic ointment can be prepared by mixing 0.5 to 5.0 grams of N¹,N³-bis(2-ethylhexyl)-1,2,3-propanetriamine diundecylenate with enough white ointment (U.S.P.) to make 100 grams of ointment.

55 Another excellent way to apply the novel compositions of my invention is in the form of an aerosol. Aerosols provide a good carrier and efficient mode of application for topical therapy in the treatment of superficial fungous infections.

60 The following table sets out the antifungal effects of some of the novel compounds of my invention. The

compounds set out in Table I were found to inhibit completely the described organism at the described minimum inhibition concentration.

TABLE I
Minimum Inhibitory Concentrations in Parts per Million

Test Compound	Test Organism			
	<i>Aspergillus niger</i>	<i>Candida albicans</i>	<i>Penicillium chrysogenum</i>	<i>Fusarium oxysporum</i>
$N^1,2\text{-dimethyl-}N^1,N^3\text{-bis(2-ethylhexyl)-1,2,3-propanetriamine dipropionate}$	500-100	500-1,000	10-100	10-100
$N^1,2\text{-dimethyl-}N^1,N^3\text{-bis(2-ethylhexyl)-1,2,3-propanetriamine tripropionate}$	100-500	100-500	100-500	10-100
$N^1,2\text{-dimethyl-}N^1,N^3\text{-bis(2-ethylhexyl)-1,2,3-propanetriamine dicaprylate}$	500-1,000	500-1,000	100-500	10-100
$N^1,2\text{-dimethyl-}N^1,N^3\text{-bis(2-ethylhexyl)-1,2,3-propanetriamine tricaprylate}$	100-500	100-500	10-100	10-100
$N^1,N^3\text{-bis(2-ethylhexyl)-2-methyl-1,2,3-propanetriamine dipropionate}$	100-500	100-500	10-100	10-100
$N^1,N^3\text{-bis(2-ethylhexyl)-2-methyl-1,2,3-propanetriamine dicaprylate}$	100-500	100-500	10-100	10-100
$N^1,N^3\text{-bis(2-ethylhexyl)-2-methyl-1,2,3-propanetriamine tricaprylate}$	100-500	100-500	10-100	10-100

The following examples further illustrate my invention, but it is not intended that my invention be limited to the compounds, etc., set out therein. Rather, it is intended that equivalents obvious to those skilled in the art be included within the scope of my invention as claimed.

EXAMPLE I

To a beaker containing 32.7 grams of $N^1,2\text{-dimethyl-}N^1,N^3\text{-bis(2-ethylhexyl)-1,2,3-propanetriamine}$ were added 22.2 grams of propionic acid. The mixture was thoroughly stirred and left standing until the heat of reaction had subsided. The resulting compound was $N^1,2\text{-dimethyl-}N^1,N^3\text{-bis(2-ethylhexyl)-1,2,3-propanetriamine tripropionate}$.

EXAMPLE II

34.1 grams of $N^1,N^3\text{-bis(2-ethylhexyl)-2-methyl-1,2,3-propanetriamine}$ were treated as in Example I with 28.8 grams of caprylic acid and the resulting compound was $N^1,N^3\text{-bis(2-ethylhexyl)-2-methyl-1,2,3-propanetriamine dicaprylate}$.

EXAMPLE III

32.7 grams of $N^1,2\text{-dimethyl-}N^1,N^3\text{-bis(2-ethylhexyl)-1,2,3-propanetriamine}$ were treated as in Example I with 18.4 grams of undecylenic acid and the resulting compound was $N^1,2\text{-dimethyl-}N^1,N^3\text{-bis(2-ethylhexyl)-1,2,3-propanetriamine mono-undecylenate}$.

EXAMPLE IV

34.1 grams of $N^1,N^3\text{-bis(2-ethylhexyl)-2-methyl-1,2,3-propanetriamine}$ were treated as in Example I with 14.8 grams of propionic acid and the resulting compound was $N^1,N^3\text{-bis(2-ethylhexyl)-2-methyl-1,2,3-propanetriamine dipropionate}$.

EXAMPLE V

32.7 grams of $N^1,2\text{-dimethyl-}N^1,N^3\text{-bis(2-ethylhexyl)-1,2,3-propanetriamine}$ were treated as in Example I with 43.3 grams of caprylic acid and the resulting compound was $N^1,2\text{-dimethyl-}N^1,N^3\text{-bis(2-ethylhexyl)-1,2,3-propanetriamine tricaprylate}$.

EXAMPLE VI

34.1 grams of $N^1,N^3\text{-bis(2-ethylhexyl)-2-methyl-1,2,3-propanetriamine}$ were treated as in Example I with 18.4 grams of undecylenic acid and the resulting compound was $N^1,N^3\text{-bis(2-ethylhexyl)-2-methyl-1,2,3-propanetriamine mono-undecylenate}$.

EXAMPLE VII

32.7 grams of $N^1,2\text{-dimethyl-}N^1,N^3\text{-bis(2-ethylhexyl)-1,2,3-propanetriamine}$ were treated as in Example I with

7.4 grams of propionic acid and the resulting compound was $N^1,2\text{-dimethyl-}N^1,N^3\text{-bis(2-ethylhexyl)-1,2,3-propanetriamine mono-propionate}$.

EXAMPLE VIII

34.1 grams of $N^1,N^3\text{-bis(2-ethylhexyl)-2-methyl-1,2,3-propanetriamine}$ were treated as in Example I with 14.4 grams of caprylic acid and the resulting compound was $N^1,N^3\text{-bis(2-ethylhexyl)-2-methyl-1,2,3-propanetriamine mono-caprylate}$.

EXAMPLE IX

32.7 grams of $N^1,2\text{-dimethyl-}N^1,N^3\text{-bis(2-ethylhexyl)-1,2,3-propanetriamine}$ were treated as in Example I with 36.9 grams of undecylenic acid and the resulting compound was $N^1,2\text{-dimethyl-}N^1,N^3\text{-bis(2-ethylhexyl)-1,2,3-propanetriamine diundecylenate}$.

EXAMPLE X

34.1 grams of $N^1,N^3\text{-bis(2-ethylhexyl)-2-methyl-1,2,3-propanetriamine}$ were treated as in Example I with 55.3 grams of undecylenic acid and the resulting compound was $N^1,N^3\text{-bis(2-ethylhexyl)-2-methyl-1,2,3-propanetriamine triundecylenate}$.

EXAMPLE XI

32.7 grams of $N^1,2\text{-dimethyl-}N^1,N^3\text{-bis(2-ethylhexyl)-1,2,3-propanetriamine}$ were treated as in Example I with 14.8 grams of propionic acid and the resulting compound was $N^1,2\text{-dimethyl-}N^1,N^3\text{-bis(2-ethylhexyl)-1,2,3-propanetriamine dipropionate}$.

EXAMPLE XII

34.1 grams of $N^1,N^3\text{-bis(2-ethylhexyl)-2-methyl-1,2,3-propanetriamine}$ were treated as in Example I with 43.3 grams of caprylic acid and the resulting compound was $N^1,N^3\text{-bis(2-ethylhexyl)-2-methyl-1,2,3-propanetriamine tricaprylate}$.

EXAMPLE XIII

32.7 grams of $N^1,2\text{-dimethyl-}N^1,N^3\text{-bis(2-ethylhexyl)-1,2,3-propanetriamine}$ were treated as in Example I with 14.4 grams of caprylic acid and the resulting compound was $N^1,2\text{-dimethyl-}N^1,N^3\text{-bis(2-ethylhexyl)-1,2,3-propanetriamine mono-caprylate}$.

EXAMPLE XIV

34.1 grams of $N^1,N^3\text{-bis(2-ethylhexyl)-2-methyl-1,2,3-propanetriamine}$ were treated as in Example I with 7.4 grams of propionic acid and the resulting compound was $N^1,N^3\text{-bis(2-ethylhexyl)-2-methyl-1,2,3-propanetriamine mono-propionate}$.

EXAMPLE XV

32.7 grams of $N^1,2\text{-dimethyl-}N^1,N^3\text{-bis(2-ethylhexyl)-1,2,3-propanetriamine}$ were treated as in Example I with 55.3 grams of undecylenic acid and the resulting compound was

ound was $N^1,2$ -dimethyl- N^1,N^3 -bis(2-ethylhexyl)-1,2,3-propanetriamine triundecylenate.

EXAMPLE XVI

34.1 grams of N^1,N^3 -bis(2-ethylhexyl)-2-methyl-1,2,3-propanetriamine were treated as in Example I with 22.2 grams of propionic acid and the resulting compound was N^1,N^3 -bis(2-ethylhexyl)-2-methyl-1,2,3-propanetriamine tripropionate.

EXAMPLE XVII

32.7 grams of $N^1,2$ -dimethyl- N^1,N^3 -bis(2-ethylhexyl)-1,2,3-propanetriamine were treated as in Example I with 28.8 grams of caprylic acid and the resulting compound was $N^1,2$ -dimethyl- N^1,N^3 -bis(2-ethylhexyl)-1,2,3-propanetriamine dicaprylate.

EXAMPLE XVIII

34.1 grams of N^1,N^3 -bis(2-ethylhexyl)-2-methyl-1,2,3-propanetriamine were treated as in Example I with 36.9 grams of undecylenic acid and the resulting compound was N^1,N^3 -bis(2-ethylhexyl)-2-methyl-1,2,3-propanetriamine diundecylenate.

Now having described my invention, what I claim is:

1. As a composition of matter, triamine acid salts having the following formula:

wherein R represents a member selected from the group consisting of hydrogen and methyl, with the proviso that if one R is methyl then the other R must be hydrogen; and

R^1 represents a member selected from the group consisting of caprylic, propionic and undecylenic acids, and x is selected from the class consisting of 0 and 1, with the proviso that at least one x is 1.

5. 2. $N^1,2$ - dimethyl - N^1,N^3 -bis(2-ethylhexyl)-1,2,3-propanetriamine mono-propionate.
3. N^1,N^3 - bis(2-ethylhexyl)-2-methyl-1,2,3-propanetriamine tripropionate.
4. $N^1,2$ -dimethyl - N^1,N^3 - bis(2-ethylhexyl)-1,2,3-propanetriamine dicaprylate.
5. N^1,N^3 - bis(2-ethylhexyl)-2-methyl-1,2,3-propanetriamine tricaprylate.
6. N^1,N^3 - bis(2-ethylhexyl)-2-methyl-1,2,3-propanetriamine triundecylenate.
10. 7. The composition of claim 1 wherein R^1 is caprylic acid.
8. The composition of claim 1 wherein R^1 is propionic acid.
9. The composition of claim 1 wherein R^1 is undecylenic acid.
